United States Patent Office

Des. 198,610
Patented July 7, 1964

198,610

CARGO AIR TRANSPORT

Vincent J. Burnelli, 9250 Piney Branch Road,
Silver Spring, Md.

Filed Nov. 12, 1963, Ser. No. 77,371

Term of patent 14 years

(Cl. D71—1)

Fig. 1

Fig. 2

Fig. 3

Fig. 4

Fig. 5

FIG. 1 is a side elevational view of the cargo air transport showing my new design.

FIG. 2 is a front elevational view thereof.

FIG. 3 is a top plan view thereof.

FIG. 4 is a sectional view taken on line 4-4 of FIG. 5.

FIG. 5 is a bottom plan view thereof.

I claim:

The ornamental design for a cargo air transport, as shown.
